UNITED STATES PATENT OFFICE.

FREDERICK A. PRESTON, OF HIGHLAND PARK, ILLINOIS, ASSIGNOR TO THE P & M COMPANY, OF CHICAGO, ILLINOIS, A CORPORATION OF ILLINOIS.

RAIL ANCHOR.

Application filed March 17, 1924. Serial No. 699,817.

To all whom it may concern:

Be it known that I, FREDERICK A PRESTON, a citizen of the United States, residing at Highland Park, in the county of Lake and 5 State of Illinois, have invented certain new and useful Improvements in Rail Anchors, of which the following is a specification.

My invention relates to rail anchors of the type adapted by contact with a tie or other 10 fixed part of the track to hold the rail from creeping or moving longitudinally.

It is the principal object of my invention to provide an improved form and arrangement of parts comprising a member applied 15 to the flange of a rail from one side thereof, and a second member applied to the rail from the other side, one or both of such members having gripping engagement with the base flange of the rail, and said members 20 having snap engagement with each other, whereby they are held interlocked in their operative working positions with respect to the flange.

It is another object of my invention to 25 improve devices of this type in sundry details, hereinafter pointed out. The preferred means by which I have accomplished my several objects are illustrated in the drawing and are hereinafter specifically 30 described. That which I believe to be new and desire to cover by Letters Patent is set forth in the claims.

In the drawing,

Fig. 1 is a face view of the preferred form 35 of my improved rail anchor applied to a rail, which is shown in section, the figure showing also by dotted lines the normal opening of the jaws of the gripping members.

Fig. 2 is a face view of one of the members shown in Fig. 1, partly applied to a rail.

Fig. 3 is a fragmentary view, showing 40 one member of the anchor in final applied position, and with the other member in its initial position ready to be applied; and

Fig. 4 is a bottom plan view of the member shown in Fig. 2.

Referring to the several figures of the 45 drawing, in which corresponding parts are indicated by the same reference characters, 10 and 11 indicate the opposite side por-

tions of the base flange of a rail, the head of which has been broken away for clearness of illustration. In Fig. 1, the rail is shown in position upon a cross tie 12 of any approved type.

My improved rail anchor comprises two members, one of which is applied from the left in Fig. 1, and the other of which is applied from the right. The first named member is shown comprising a cross plate or bar 13, provided with a depending plate 14 which serves as the abutment against the tie 12. At its end portion, the bar 13 is provided with a jaw 15 which is turned backwardly along the bar so as to grip the base flange 10, the dotted line position in Fig. 1 showing the distortion to which the jaw is subjected in being driven into gripping position upon the flange 10 from the left in Fig. 1. At its opposite end portion, the bar 13 is provided with an upwardly extending lug 16 which is preferably relatively low so as to avoid excessive distortion of the jaw 15 during its application to a rail, but which is of sufficient height to snap into position opposite the edge of the base flange 11 when the member is driven toward the right into its final operative position, as shown in Fig. 1. The member comprising the jaw 15, the tie abutment plate 14 and the upward extension 16 is preferably made in the form of a forging from a fairly low grade steel, the arrangement being such that the member by itself when applied in its operative position, as shown in Fig. 1, has a fairly strong grip upon the rail and may be applied without danger of destroying the resiliency of the metal.

The other member of my improved anchor is in the form of a clip or yoke, comprising a jaw or arm 17 adapted to engage the upper face of the flange 11 and a jaw or arm 18 adapted to engage the bottom face of the bar 13.

As is clearly shown by dotted lines in Fig. 1, the opening between the jaws 17 and 18 is insufficient normally for accommodating the thickness of material between such jaws in their applied position, as shown in Fig. 1. The result is that the clip comprising the arms 17 and 18 must be driven into position from the initial applied position, as shown

in Fig. 3. Inasmuch as the clip 17-18 is to be formed as a forging from high grade steel, it will be understood that the resistance of the clip in being driven into final operative position is very considerable, with the result that under ordinary normal conditions the arm 17 cuts into the flange 11, forming a transverse groove 19 therein. When the clip reaches its final operative position, as shown in Fig. 1, an upturned lug or shoulder 20 formed on the end portion of the arm 18 snaps past a shoulder 21 formed on the bottom face of the bar 13 so as to have interlocking engagement therewith. The shoulder 21, like the shoulder 16, is preferably of such height as to avoid excessive distortion of the clip 17 and thereby avoid any appreciable reduction in spring pressure of the clip when the lug 20 thereof snaps over the shoulder 21.

For holding the clip from slipping out of engagement with the shoulder 21, ribs 22, 23 are provided extending longitudinally of the bar 13 at opposite ends of the shoulder 21 for engagement with opposite faces of the arm 18, as will be readily understood.

By reason of the fact that the member comprising the arms 17 and 18 is formed of high carbon steel, such clip has a very strong grip upon the base flange, such grip being particularly effective for preventing longitudinal movement of the rail by reason of the fact that the arm 17 engages within a groove 19, as above described. Also by reason of the strength of the clip, it will be understood that the interlocking engagement between the upward extension 20 of the clip and the shoulder 21 of the other member of the anchor is very strong, serving very effectively for holding the members in their operative gripping engagement with the base flange of the rail.

By reason of having an interlocking of the two members, characterized by a shoulder on one of the members having snap engagement with a portion of the other member, the retention of the two members in operative position upon the flange is made much more certain and much more reliable than is the case when reliance is placed upon the tight fit of the parts or upon the friction of the engagement, as is done in some instances in the prior art. Furthermore, the shoulder 16, in addition to cooperating with the jaw 15 to provide a firm grip on opposite edges of the rail base, serves as an abutment to hold the bar 13 and jaw 15 from being displaced when the clip 17 is driven to its rail gripping position. So far as I am aware, I am the first in the art to provide a construction of this type in which an actual interlocking of this type is provided, and I therefore desire to cover the feature broadly.

By providing a two part anchor, compris-

ing one member formed of low grade metal and provided with the tie abutment, and a second member of high grade metal by which an effective gripping is obtained, the cost of the metal making up the anchor is very materially reduced, and the manufacture of the device is correspondingly facilitated. This feature is accordingly seen to be of very considerable importance, and my claims are to be construed accordingly.

While I have shown the groove 19 as being cut in the top face of the flange by the clip during the application of the device to the rail I wish to have it understood that I do not wish to limit my invention to a depression in the form of a transverse groove, or to the production of such depression in any particular manner, except so far as the same are specifically claimed, the important feature being that a part of the anchor engages a depression in the rail at some point removed from the edge of the flange.

While I prefer to embody my invention in the form as illustrated in the drawing, it will be understood that I do not desire to be limited to the precise details of construction as there shown, except as the same is hereinafter specifically claimed, inasmuch as it is evident that various changes might well be made in the form of the device without departing from the spirit of my invention.

I claim:

1. A rail anchor comprising a resilient member adapted to be driven from one side of a rail into resilient gripping engagement with the base flange, and a second member adapted to be driven from the other side of the rail into gripping engagement with the base flange and locking engagement with the first named member.

2. A rail anchor comprising a resilient member adapted to be driven laterally with respect to a rail into resilient gripping engagement with the base flange at one side thereof, a shoulder on said member adapted to snap into position opposite the edge of the flange at the opposite side of the rail, and a second member adapted to be driven into gripping engagement with the flange from the side at which said shoulder is located and into locking engagement with the first named member.

3. A rail anchor comprising a resilient member adapted to be driven laterally with respect to a rail into resilient gripping engagement with the base flange at one side thereof, a shoulder on said member adapted to snap into position opposite the edge of the flange at the opposite side of the rail, a second member adapted to be driven into gripping engagement with the flange from the side at which said shoulder is located, and a second shoulder on one of said members having snap engagement with a portion

of the other member for holding said two members in gripping position on the flange.

4. A rail anchor comprising a resilient member adapted to be driven from one side of a rail into resilient gripping engagement with the base flange, a second member adapted to be driven from the other side of the rail into gripping engagement with the flange, and a shoulder on one of said members past which a part of the other member is driven so as to have snap engagement therewith for holding said two members in gripping position on the flange.

5. A rail anchor comprising a resilient member adapted to be driven from one side of a rail into resilient gripping engagement with the base flange, a second member adapted to be driven from the other side of the rail into gripping engagement with the flange, and shoulders on said members respectively adapted by snap engagement with each other to hold said members in gripping position on the flange.

6. A rail anchor comprising a resilient member adapted to be driven from one side of a rail into resilient gripping engagement with the base flange, and a second member adapted to be driven from the other side of the rail into position embracing both the flange and the first named member and into locking engagement with the first named member.

7. A rail anchor comprising a resilient member adapted to be driven from one side of a rail into position embracing the base flange at that side with spring pressure, and a second member adapted to be driven from the other side of the rail into gripping engagement with the flange and gripping and locking engagement with the first named member.

8. A rail anchor comprising a resilient member adapted to be driven from one side of a rail into resilient gripping engagement with the base flange, a second member adapted to be driven from the other side of the rail into position embracing and gripping both the flange and the first named member, and a shoulder on one of said members having snap engagement with a part of the other member for holding said two members in gripping position on the flange.

9. A rail anchor comprising a resilient member adapted to be driven from one side of the rail into resilient gripping engagement with the base flange, a shoulder on said member adapted to snap into position opposite the edge of the flange at the opposite side of the rail, a second member adapted to be driven from the side of the rail at which said shoulder is located into position embracing and gripping both the flange and the first named member, and a second shoulder on one of said members having snap engagement with a part of the other member

for holding said two members in gripping position on the flange.

10. A rail anchor comprising a resilient member adapted to be driven from one side of a rail into resilient gripping engagement with the base flange, a second member adapted to be driven from the other side of the rail into position embracing and gripping both the flange and the first named member, and a shoulder on the bottom face of the first named member adapted to have snap engagement with the end portion of the second member for holding said two members in gripping position on the flange.

11. A rail anchor comprising a resilient member adapted to be driven from one side of the rail into resilient gripping engagement with the base flange, a shoulder on said member adapted to snap into position opposite the edge of the flange at the opposite side of the rail, a second member adapted to be driven from the side of the rail at which said shoulder is located into position embracing and gripping both the flange and the first named member, and a second shoulder on the bottom face of the first named member adapted to have snap engagement with the end portion of the second member for holding said two members in gripping position on the flange.

12. A rail anchor comprising a member adapted to be driven from one side of a rail into gripping and locking engagement with the base flange, a tie abutment depending from said member, and a second member adapted to be driven from the other side of the rail into gripping engagement with the base flange and locking engagement with the first named member.

13. In a rail anchor, the combination of a member formed of low grade steel comprising a jaw at one end adapted to be driven from one side of a rail into gripping and locking engagement with the base flange, a tie abutment depending from said member, and a second member formed of high grade steel adapted to be driven from the other side of the rail into gripping engagement with the base flange and locking engagement with the first named member.

14. In a rail anchor, the combination of a member formed of low grade steel comprising a jaw at one end adapted to be driven from one side of a rail into resilient gripping engagement with the base flange, a tie abutment depending from said member, a second member formed of high grade steel adapted to be driven from the other side of the rail into gripping engagement with the base flange, and a shoulder on one of said members having snap engagement with a part of the other member for holding said two members in gripping position on the flange.

15. In a rail anchor, the combination of

1 a member formed of low grade steel comprising a jaw at one end adapted to be driven from one side of a rail into resilient gripping engagement with the base flange,
 5 a tie abutment depending from said member, a second member formed of high grade steel adapted to be driven from the other side of the rail into gripping engagement with the base flange, and a shoulder on said
 10 first named member having snap engagement with the end portion of the other member for holding said two members in gripping position on the flange.

16. A rail anchor comprising a member
 15 adapted to be driven from one side of a rail into position embracing the base flange at that side, a second member of high grade steel adapted to be driven from the other side of the rail into gripping engagement
 20 with the flange, the arrangement being such that said second member in its movement into gripping position cuts a groove in the upper face of the flange, and interlocking means on said two members for holding said
 25 second member in gripping position on the flange.

17. A rail anchor comprising a member adapted to be driven from one side of a rail into position embracing the base flange at
 30 that side, a second member of high grade steel adapted to be driven from the other side of the rail into gripping engagement with the flange, the arrangement being such that said second member in its movement
 35 into gripping position cuts a groove in the upper face of the flange, and a shoulder on one of said members having snap engagement with a part of the other member for holding said second member in gripping position on the flange.

18. In a rail anchor, the combination of a member formed of low grade steel comprising a jaw at one end adapted to be driven from one side of a rail into gripping engagement with the base flange, a tie abutment depending from said member, a shoulder on said member adapted to have snap engagement with the edge of the flange at the opposite side of the rail for holding said
 45 member in gripping position on the flange, a second member formed of high grade steel adapted to be driven from the other side of the rail into gripping engagement with the base flange, the arrangement being such that
 50 said second member in its movement into gripping position cuts a groove in the upper face of the flange, and a second shoulder on said first named member having snap engagement with a portion of said second member for holding said two members in
 55 gripping position on the flange.

19. A rail anchor comprising a part adapted for engagement with a depression in the face of the rail at a point removed
 60 from the edge of the flange to hold the an-

chor from movement longitudinally of the rail, and means for holding the anchor from movement with respect to a tie.

20. A rail anchor comprising a member adapted to grip the base flange of a rail and
 70 adapted by engagement with a depression in the face of the rail at a point removed from the edge of the flange to hold the anchor from movement longitudinally of the rail, and means adapted by engagement with
 a tie to hold the anchor in position.

21. A rail anchor comprising a part adapted by engagement with a transverse groove in one of the faces of the base flange
 80 of a rail at a point removed from the edge of the flange to hold the anchor from movement longitudinally of the rail, and means for holding the anchor from movement with respect to a tie.

22. A rail anchor comprising a clip adapted to embrace the base flange of a rail, the end of the clip being adapted by engagement with a transverse groove in one of the faces of the flange at a point removed from the edge of the flange to hold the anchor from movement longitudinally of the rail, and
 90 means for holding the anchor from movement with respect to a tie.

23. A rail anchor comprising a jaw adapted to grip the base flange of a rail, said jaw being adapted by engagement with a transverse groove in the upper face of the flange at a point removed from the edge of the flange to hold the anchor from movement longitudinally of the rail, and means
 100 for holding the anchor from movement with respect to a tie.

24. A rail anchor comprising a bearing for the top face of the base flange of a rail, a bearing for the bottom face of the flange, one of said bearings being adapted by engagement with a depression in the corresponding face of the flange at a point removed from the edge of the flange to hold the anchor from movement longitudinally of the rail, and means for holding the anchor from movement with respect to a tie.

25. A rail anchor adapted to be applied to a rail by movement transversely of the rail into engagement with the base flange of the rail, comprising a bearing for the top face of the flange, a bearing for the bottom face of the flange, one of said bearings being brought by the transverse movement into engagement with a depression in the corresponding face of the flange at a point removed from the edge of the flange for holding the anchor from movement longitudinally of the rail, and means for holding the anchor from movement with respect to a tie.

26. A rail anchor adapted to be applied to a rail by movement transversely of the rail into engagement with the base flange, comprising a bearing for one of the faces of

the flange, and means for holding the anchor from movement with respect to a tie, the said bearing being adapted upon its movement transversely of the rail to cut a transverse groove in the face of the flange for assisting in holding the anchor from movement longitudinally of the rail.

27. A rail anchor comprising a clip adapted to be applied in gripping position on a rail by movement transversely of the rail into engagement with the base flange, and means for holding the anchor from movement with respect to a tie, one end of the clip being adapted upon its movement transversely of the rail to cut a transverse groove in the face of the flange for assisting in holding the anchor from movement longitudinally of the rail.

28. A rail anchor adapted to be applied to a rail by movement transversely of the rail into engagement with the base flange, comprising a bearing for one of the faces of the flange, and means for holding the anchor from movement with respect to a tie, the said bearing being adapted upon its movement transversely of the rail to cut a transverse groove in the face of the flange from a point removed from the edge of the flange and extending toward the web of the rail for assisting in holding the anchor from movement longitudinally of the rail.

29. A rail anchor comprising a clip adapted to be applied in gripping position on a rail by movement transversely of the rail into engagement with the base flange, and means for holding the anchor from movement with respect to a tie, the end of the upper arm of the clip being adapted upon its movement transversely of the rail to cut a transverse groove in the upper face of the flange from a point removed from the edge of the flange and extending toward the web of the rail for assisting in holding the anchor from movement longitudinally of the rail.

30. A rail anchor comprising a member formed of low grade steel and provided at one end with a jaw adapted to be driven into resilient gripping engagement with the base flange and formed at the other end with a relatively low shoulder adapted to snap over the edge of the rail base, and a second member adapted to be driven into position embracing both the flange and the first named member.

31. A rail anchor comprising a rail base embracing member and a gripping member adapted to be driven into gripping engagement with one flange of the rail base and with said base embracing member; one of said members being provided with a portion having a snap engagement with the other member for holding the anchor in gripping position on the rail.

32. A rail anchor comprising a member

for engaging the under surface of a rail base and a gripping member adapted to be driven into gripping engagement with one flange of said rail base and with said first mentioned member; one of said members being provided with a portion having a snap engagement with the other member for holding the anchor in gripping position on the rail.

33. A rail anchor comprising a member for engaging the under surface of the rail base and a gripping member adapted to be driven into gripping engagement with one flange of said rail base and with said first mentioned member; said members being formed with coengaging shoulder portions adapted to have a snap engagement with each other for holding the anchor in gripping position on the rail.

34. A rail anchor comprising a member for engaging the under surface of the rail base and a gripping member adapted to be driven into gripping engagement with the upper surface of the rail base and with the under surface of said first mentioned member and having a snap engagement with the latter, said gripping member being formed to confine it in operative engagement with the rail to a point remote from the adjacent edge of the rail base.

35. A device for preventing the longitudinal creep of railroad rails comprising a plate adapted to extend transversely under the rail base, a member having upper and lower jaws adapted, respectively, to extend transversely over one of the rail base flanges and under said plate, and having a snap engagement with said plate to hold said members in their operative position on the rail; said upper jaw being formed to provide clearance between it and the upper surface of the rail base adjacent the edge of said base.

36. A device for preventing the longitudinal creep of railroad rails, comprising a member having upper and lower jaws adapted, respectively, to extend transversely over and under one of the rail base flanges, and means interposed between the upper side of the lower jaw and the under side of the rail base for decreasing the effective distance between said jaws sufficiently to make it necessary to spring said member from its normal shape when driving it transversely onto said base flange.

37. A device for preventing the longitudinal creep of railroad rails, comprising a member having upper and lower jaws adapted, respectively, to extend transversely over and under one of the rail base flanges, and a plate interposed between the upper side of the lower jaw and the under side of the rail base for decreasing the effective distance between said jaws sufficiently to make it necessary to spring said member from its

normal shape when driving it transversely onto said base flange, said plate having means coengaging with the rail base to prevent slippage of the plate transversely of the rail base.

38. A device for preventing the longitudinal creep of railroad rails, comprising a member having upper and lower jaws adapted, respectively, to extend transversely over and under one of the rail base flanges, and a plate interposed between the upper side of the lower jaw and the under side of the rail base for decreasing the effective distance between said jaws sufficiently to make it necessary to spring said member from its normal shape when driving it transversely onto said base flange, said plate having means co-engaging with the rail base to prevent slippage of the plate transversely of the rail base, and said lower jaw and said plate having co-engaging means to prevent slippage of said member transversely of said plate.

39. A device for preventing the longitudinal creep of railroad rails, comprising a member having upper and lower jaws adapted, respectively, to extend transversely over and under one of the rail base flanges, and a plate interposed between the upper side of the lower jaw and the under side of the rail base for decreasing the effective distance between said jaws sufficiently to make it necessary to spring said member from its normal shape when driving it transversely onto said base flange, said plate having means co-engaging with the rail base to prevent slippage of the plate transversely of the rail base, and said lower jaw and said plate having co-engaging means to prevent slippage of said member transversely and longitudinally of said plate.

40. A device for preventing the longitudinal creep of railroad rails, comprising a plate adapted to extend transversely under the rail base and having upstanding projections adapted to engage the edges of the respective base flanges, and a member having upper and lower jaws adapted, respectively, to extend transversely over one of the rail base flanges and under said plate, the distance between the jaws of said member, when the latter is free of the rail and said plate, being less than the thickness of that part of the base flange and the plate embraced by said jaws.

41. A device for preventing the longitudinal creep of railroad rails, comprising a plate adapted to extend transversely under the rail base and having on its top side upstanding projections adapted to engage the edges of the respective base flanges and on its bottom side a downwardly extending shoulder, and a member having upper and lower jaws adapted, respectively, to extend transversely over one of the rail base flanges

and under said plate, the distance between the jaws of said member, when the latter is free of the rail and said plate, being less than the thickness of that part of the base flange and the plate embraced by said jaws, 70 said lower jaw having an upstanding projection adapted to engage said shoulder when the device is applied to the rail.

42. Means for preventing the longitudinal creep of railroad rails comprising a plate member adapted to extend transversely under the rail base and having upstanding projections adapted to engage the edges of the respective base flanges, and a device having an upper jaw and a lower jaw member adapted, respectively, to extend transversely over one of the rail base flanges and under said plate member, the distance between said jaw and said jaw member, when said device is free of the rail and said plate member, being less than the thickness of that part of the base flange and the plate member embraced by said jaw and jaw member, one of said members having spaced ribs 80 while the other of said members is formed so that a portion thereof will lie between said ribs when the members are on the rail, for the purpose specified.

43. Means for preventing the longitudinal creep of railroad rails comprising a plate member adapted to extend transversely under the rail base and having on its top side upstanding projections adapted to engage the edges of the respective base flanges and on its bottom side a downwardly extending shoulder, and a device having an upper jaw and a lower jaw member adapted, respectively, to extend transversely over one of the rail base flanges and under said plate member, the distance between said jaw and said jaw member, when said device is free of the rail and said plate member, being less than the thickness of that part of the base flange and the plate member embraced by said jaw and jaw member, one of said members having spaced ribs while the other of said members is formed so that a portion thereof will lie between said ribs, said jaw member having an upstanding projection adapted to engage said shoulder when the device is applied to the rail. 100

44. A device for preventing the longitudinal creep of railroad rails comprising a plate adapted to extend transversely under the rail base, and a member having upper and lower jaws adapted, respectively, to extend transversely over one of the rail base flanges and under said plate, the distance between the jaws of said member, when the latter is free of the rail and said plate, being less than the thickness of that part of the base flange and the plate embraced by said jaws, the length of said jaws not exceeding substantially one-half the width of the rail base. 110 120 125 130

45. A device for preventing the longitudinal creep of railroad rails comprising a plate adapted to extend transversely under the rail base, said plate having means co-
5 engaging with the rail base to prevent slip-
page of the plate transversely of the rail
base, and a member having upper and lower
jaws adapted, respectively, to extend trans-
versely over one of the rail base flanges and
10 under said plate, the distance between the
jaws of said member, when the latter is free
of the rail and said plate, being less than
the thickness of that part of the base flange
and the plate embraced by said jaws, the
15 length of said jaws not exceeding substan-
tially one-half the width of the rail base.
46. A device for preventing the longitudi-
nal creep of railroad rails comprising a
plate adapted to extend transversely under
20 the rail base, and a member having upper
and lower jaws adapted, respectively, to ex-
tend transversely over one of the rail base
flanges and under said plate, the distance be-
tween the jaws of said member, when the
25 latter is free of the rail and said plate, be-
ing less than the thickness of that part of
the base flange and the plate embraced by
said jaws, the length of said jaws not ex-
ceeding substantially one-half the width of
- the rail base, said plate having means co- 30
engaging with the rail base to prevent slip-
page of the plate transversely of the rail
base, and said lower jaw and said plate
having co-engaging means to prevent slip-
page of said member transversely of said 35
plate.
47. A device for preventing the longitudi-
nal creep of railroad rails comprising a
plate adapted to extend transversely under
40 the rail base, and a member having upper
and lower jaws adapted, respectively, to ex-
tend transversely over one of the rail base
flanges and under said plate, the distance
between the jaws of said member, when the
45 latter is free of the rail and said plate,
being less than the thickness of that part
of the base flange and the plate embraced
by said jaws, the length of said jaws not
exceeding substantially one-half the width
50 of the rail base, said plate having means co-
engaging with the rail base to prevent slip-
page of the plate transversely of the rail
base, and said lower jaw and said plate
having co-engaging means to prevent slip-
page of said member transversely and lon- 55
gitudinally of said plate.

FREDERICK A. PRESTON.
